Attorney

UNITED STATES PATENT OFFICE.

GEORGE W. CHESNUT, OF CARTWRIGHT, PENNSYLVANIA.

WHEEL AND RAIL CHOCK-BLOCK.

1,193,512.

Specification of Letters Patent.

Patented Aug. 8, 1916.

Application filed July 29, 1915. Serial No. 42,514.

To all whom it may concern:

Be it known that I, GEORGE W. CHESNUT, a citizen of the United States, residing at Cartwright, in the county of Elk and State 5 of Pennsylvania, have invented certain new and useful Improvements in Wheel and Rail Chock-Blocks, of which the following is a specification.

This invention relates to improvements in 10 railway-brakes, and more specifically to wheel and rail chock-blocks.

The object of my invention is to provide a chock-block for use especially in retaining a car upon a transfer or turn-table.

15 My device is securely fastened upon the transfer or turn-table in proper relative position with respect to the track so that it may be locked in operative position upon the track simply by pushing the locking arm 20 forward, and unlocked by a reverse movement.

Furthermore, my device is extremely simple in construction and operation, economical in manufacturing cost, durable, and 25 efficient in operation as it positively locks a car upon a transfer-table or turn-table.

Other objects of this invention not at this time more particularly enumerated, will be clearly understood from the detailed description and drawings forming a part of 30 this specification.

Furthermore, this invention consists in the novel arrangement and combination of parts more particularly described in the following specification and embodied in the 35 claims appended hereunto and forming a part of this application.

Referring now to the drawings, which are merely illustrative of my invention, Figure 1 40 is a side elevation showing the relative position of my chock-block in operative position with respect to a car wheel and rail mounted upon a transfer-table. Fig. 2 is a similar view in inoperative position. Fig. 3 is a detail sectional view taken on the line 3—3 of Fig. 1.

Referring further to the drawings, wherein similar reference characters designate similar parts throughout the respective 50 views, 1 designates a main-line track upon which a transfer-table 2 is adapted to run. The construction of the transfer-table is immaterial, since my device is so constructed that it may be fastened upon various foundations without necessitating such changes in 55 construction as to deviate from the principle

of construction shown in my invention. For purposes of illustration, I have shown an I-beam 3 as forming a part of the platform of the transfer-table, transversely of which there is mounted a rail track 4. The wheel 5 of the car (not shown) to be transferred is adapted to run upon the track 4 and to be retained thereon by my chock-block during the course of its transfer from one track to 65 another.

At a certain point upon the I-beam 3 and spaced apart a certain distance from the side of the rail 4, there is fixedly mounted a bifurcated L-shaped guide member 6, which 70 may be made integral, or of two L-shaped members having their shorter arms laid parallel in juxtaposition one on top of the other, as shown in Fig. 3. The L-shaped bifurcated guide member is vertically mounted 75 upon the I-beam 3 by means of bolts 7 secured through the upper flange of said beam and the shorter arm of said plate member.

A locking arm 8, having a handle 9 upon one end, and a finger 10 upon the opposite 80 end thereof, is formed with an elongated slot 11 therethrough, angularly disposed with respect to a horizontal plane, the lower end of said slot terminating near the handle end of said arm, and a vertical slot 12 being 85 formed in continuation of said slot 11. Said arm 8 is mounted between the bifurcations of said guide member 6 and is slidably retained therebetween by means of a bolt 13 mounted transversely through said guide 90 member and through the slot in said arm.

From the construction shown and described, it is obvious that when the handle 9 of the locking arm is grasped and pushed forward, the arm will be raised upwardly 95 within the bifurcated guide member 6. When the arm 8 has moved forward until the lower end of the slot 11 contacts with the bolt 13, the finger 10 will be in a position diametrically above and spaced apart with 100 respect to the head of the rail 4. As the arm drops down and the bolt 13 engages with the top of the vertical slot 12, the finger 10 will seat upon the rail 4, thereby limiting the movement of the wheel 5 upon 105 the rail 4. The operation is reversed to withdraw the arm of my wheel and rail chock-block into inoperative position.

The utility, adaptability, and advantages of my improved form of wheel and rail 110 chock-blocks being obvious, it is unnecessary to further enlarge upon the same herein.

Having now described and pointed out the new and useful features of my invention, I do not limit myself to the shape of certain parts where the shape is not essential, nor do I restrict myself to the exact details of construction shown and described, but mean and intend to claim all equivalents and variations thereof not departing in principle from my invention and falling within the purview of the appended claims.

What I claim as my invention and desire to secure by Letters Patent is:

1. A device of the class described, in combination with a railway rail, a supporting member, a bearing thereon, and an arm having an angular slot receiving the bearing, said arm being operable upwardly and laterally into and out of proximity to the rail.
2. In a chock-block, a bearing, a slotted member in engagement therewith, and handle means on said slotted member to move the latter into and out of operative position.
3. In a chock-block, a support, a bearing thereon, and an arm having a slot in engagement with the bearing, said slot being formed to lock said arm in operative position.

4. In a wheel and rail chock-block, in combination, a vertically disposed bifurcated guide member, a bearing mounted upon said guide member transversely thereof, an arm adapted to slide within said guide member, said arm formed with an elongated slot therethrough, said bearing adapted to slidably engage with the slot in said arm, a finger formed on one end of said arm, and a handle formed on the other end of said arm.

5. In combination with a transfer-table, a bifurcated guide member vertically mounted upon said transfer-table, a bearing interposed between the sides of said guide member, an arm adapted to slide within said guide member, said arm formed with an elongated angular slot therethrough, said arm formed with a vertical slot therethrough in continuation of said angular slot, said bearing adapted to slide within said slot, a finger formed upon one end of said arm, and a handle formed upon the other end of said arm.

In testimony whereof I affix my signature hereto.

GEORGE W. CHESNUT.
